UNITED STATES PATENT OFFICE.

JULIUS BRENZINGER, OF FAIRFIELD, CONNECTICUT.

CAN-COVER-LINING MACHINE.

1,390,491.

Specification of Letters Patent. Patented Sept. 13, 1921.

Application filed April 22, 1919, Serial No. 291,905. Renewed January 31, 1921. Serial No. 441,454.

To all whom it may concern:

Be it known that I, JULIUS BRENZINGER, a citizen of the United States, residing at Fairfield, in the county of Fairfield and 5 State of Connecticut, have invented certain new and useful Improvements in Can-Cover-Lining Machines, of which the following is a specification.

In packing food stuffs and other perishable products in what are generally known as tin cans, it is obviously necessary that the container, when packed and headed, be absolutely air-tight. In the old type of solder-sealed cans, the exercise of a little care and 10 the use of a sufficient quantity of solder insured, with a reasonable degree of certainty, hermetic joints. Demand for a solderless container brought into existence the so-called "sanitary" can, in which the ends or 15 heads are secured to the body portion of the can by intercurling and compressing flanges on these parts, an operation commonly known as double seaming. Slight and unavoidable imperfections and irregularities in 20 the metal, and other causes, render it exceedingly difficult to form an air-tight double seam without the use of a suitable packing, and it therefore came to be the practice to deposit upon one of the flanges 25 to be intercurled a liquid or semi-liquid compound, self-hardening to rubber-like consistency, which provides the necessary packing and insures an hermetic joint.

This compound is generally applied to the 30 flange of the head or cover, and is deposited thereon in different ways. Most common, probably, is the process of turning the cover around underneath a nozzle through which a small stream of the compound is being discharged. Another process is that of causing 35 rotation of the cover with its edge in contact with a roller upon which a film of the compound has been deposited, whereby a proper amount of the compound is scraped from the roller and deposited on the edge of the cover-flange. Undoubtedly, both processes are 40 fairly effective, but each is subject to objection. It is obviously undesirable that any 45 of the compound be so deposited, either as to location or quantity, as to be within the can when it has been packed and sealed. Not only is it difficult to regulate the stream discharged from a nozzle, due to variations in 50 the consistency of the compound and in the pressure applied to discharge the same, but

the nozzle is likely to and often does become clogged, particularly during a temporary suspension of operations. Therefore, the quantity delivered is sometimes insufficient and unevenly deposited and sometimes excessive, in one case resulting in the formation of an imperfect seam and in the other resulting in a portion of the compound being squeezed into the interior of the can during the double seaming operation.

When the cover is manipulated to scrape the compound from a rotating roller, it is obvious that the compound will be deposited along the extreme edge only of the cover-flange. In packing what are known as 70 "high process" goods, which include almost all vegetable food stuffs, where perfect sterilization is essential, the packed and sealed can is subjected to a temperature of from 240° to 250° Fahrenheit, for a period 75 of several hours. This means a continuous internal pressure of from 15 to 20 lbs., and when the packing compound has been deposited along the extreme edge only of the cover-flange, being more or less softened by 80 the heat, a portion or portions thereof are likely to be and frequently are blown out during the process of sterilization.

The cover-flange is generally partially curled or turned when the cover is stamped from the blank, forming a shallow peripheral groove or gutter. It has been found that for best results the packing ring should be initially positioned in the bottom of this groove or gutter. Being so positioned, if the 85 amount of the compound deposited is not excessive, no portion of it can be squeezed into the interior of the can during the seaming operation nor be blown out during the process of sterilization. The principal object of the present invention is the provision of a machine for applying a seam-packing composition to can covers in properly regulated quantity along the bottom only of the peripheral groove or gutter of the cover, 90 or intermediate the edges of the cover-flange. Among other incidental objects are those of the provision of a machine in which the compound is applied to the cover-flange in a manner which permits of the use of a 95 composition of such character that it does not have to be heated to reduce it to and retain it in a liquid or semi-liquid state; and that of the provision of a machine in which a compound of initially relatively denser con- 100

sistency may be employed, whereby the process of hardening may be expedited; and all without curtailing the output capacity essential to a machine of this character.

5. My invention will be more readily understood by reference to the accompanying drawings, forming a part of this specification, in which—

10 Figure 1 is a top plan view of a machine which I consider a practical and convenient embodiment of my invention;

Fig. 2 is a vertical section thereof, taken substantially on the broken line 2—2 of Fig. 1;

15 Fig. 3 is a transverse vertical section, taken substantially on the line 3—3 of Fig. 1, and

Fig. 4 is an enlarged central sectional detail view of a can-cover and the lower ends of the telescoping plungers, hereinafter 20 described, just after the depositing operation.

Referring now to the drawings in detail, numeral 7 designates a heavy casting which provides a suitable frame supported from 25 the floor by means of standards 8 8. The top plate of this casting 7 is provided with a substantially central depression 9 which provides a support and bearings for the collar 10 fixed on the vertical shaft 11, which 30 also has bearings in the boss 12 on the cross-bar 13 of the frame. At the top of the shaft 11 is mounted a turret, in the form of a cross, providing the four radially-disposed arms 14, 15, 16 and 17 which revolve with 35 the shaft 11.

At the end of each of the arms 14, 15, 16 and 17 is mounted what may be termed a 40 double plunger, comprising an exterior plunger 18 the tubular shank 19 of which is slidable in suitable bearings at the end of the arm, and an interior plunger 20 the shank 21 of which is slidable within the tubular shank 19 of the plunger 18. The plunger or plunger-head 18 is of inverted 45 cup shape, and the plunger or plunger-head 20 fits snugly therewithin, normally projecting slightly therefrom, as shown on the right-hand side of Fig. 3, in which position it is yieldingly held by means of the coil 50 spring 22 in compression between the plunger-head 20 and the shoulder provided by the recess 23 in the plunger-head 18.

The plunger 20 is rotatively supported by 55 means of a roller 24—the further function of which will be hereinafter explained—fixed on the shank 21 above the end of the shank 19 of the plunger 18. The plunger 18 is rotatively carried at the end of a lever 25 pivoted or fulcrumed in the boss 26 with 60 which each of the arms 14, 15, 16 and 17 is provided, said lever terminating in a yoke 27 each arm of which is slotted for the reception of pins 28 28 on a collar 29 loosely seated in a groove in the shank 19, a common 65 and well-known expedient. At the other end

of each of the levers 25 25 is provided a yoke 30 the arms of which are slotted for the reception of pins 31 31 at the upper end of a rod 32 which is slidable vertically in bearings in the arm (14, 15, 16 or 17) on which the lever 25 is mounted and in the collar 10 on the shaft 11. A coil spring 33, interposed between a fixed collar 36 on the rod 32 and a shoulder provided by the recess 37 in the lever-carrying arm, serves to yieldingly retain 75 the plungers in raised or elevated positions.

At one side of the top plate of the frame 7, I form a depressed portion 38 for the reception of a tank 39, adapted to contain the liquid or semi-liquid composition to be applied to the cover-flanges. The main driving shaft 40, which will be hereinafter described, passes through this tank 39, having suitable bearings in the side walls thereof, and on this shaft 40 is mounted the roller 41, adapted to dip into the liquid 42 in said tank, as shown in Fig. 3. The location of the shaft 40, the diameter of the roller 41, and the normal vertical position of the plunger-head 20 are all so relatively adjusted that when the arms 14, 15, 16 and 17 are revolved by the shaft 11, each plunger-head 20 in turn is brought over the roller 41 with its edge immediately above the upper face of the roller.

The main driving shaft 40, to which I have hereinbefore referred, is journaled in suitable bearings provided in the frame 7 and may be driven in any desired manner, as by a pulley 43 thereon having the usual 100 connection with a source of power. Mounted on the shaft 40 is a bevel-gear 44 in mesh with a corresponding gear 45 on the horizontal shaft 46. At the other end of the shaft 46 is mounted the bevel-gear 47 in mesh with a corresponding gear 48 on the short vertical shaft 49. At the lower end of the shaft 49 is mounted the disk wheel 50 and at the lower end of the shaft 11 is mounted the star-wheel 51, the two making 105 up the well-known Geneva-stop movement. I have shown the disk-wheel 50 provided with two oppositely located pin-carrying arms 52 and 53, anti-friction rollers 54 and 55 being preferably mounted on said pins and adapted to enter radial slots 56 56 in the star-wheel 51, said wheels being inter-recessed in the usual manner, whereby upon each semi-rotation of the shaft 49, the star-wheel 51, and therewith the shaft 11 and the arms 14, 15, 16 and 17, will be turned through a quarter-revolution, with appreciable periods of rest between the turns.

On the top plate of the frame 7, opposite the roller 41 and underneath the path of 125 movement of the plungers, I provide a seat for a can head or cover 57, preferably by mounting on said plate a ring or apertured disk 58, as shown. The Geneva-stop movement is so adjusted that when the shaft 11 is 130

in a condition of rest, one of the plunger mechanisms described will be located above the roller 41, in position to be depressed against said roller to scrape therefrom a ring 5 of composition, while the opposite plunger mechanism will be located immediately above the cover-seat 58. It is to be understood that the diameter of the plunger 18 is such that the rim of the inverted cup-shaped 10 portion thereof, upon depression, will enter the groove or gutter 59 at the edge of a cover for a standard size of can, said cover being in inverted position, as clearly shown in Fig. 4.

15 Mounted at the end of the power shaft 40 is a bevel-gear 60 in mesh with a corresponding gear 61 on the horizontal shaft 62. At the other end of the shaft 62 is mounted the cam-wheel 63 for independently oscillating 20 the horizontal shaft 64 and the sleeve 65 loose thereon. Fixed upon the shaft 64 is the arm 66, so positioned and adjusted that when the shaft 11 is at rest the lower end of one of the rods 32 is immediately above 25 the anti-friction roller 67 mounted at the end of said arm 66. On the sleeve 65 is fixed the arm 68, so positioned and adjusted that under the same conditions the roller 69 at the end thereof is immediately below 30 the lower end of the opposite rod 32. In one face of the cam-wheel 63 is provided the cam-groove 70 into which projects the usual roller at the end of a lever 71 fixed upon the shaft 64. In the other face of the cam- 35 wheel is provided a cam-groove 72 (dotted lines in Fig. 2) into which projects the usual roller at the end of a lever 73 fixed upon the sleeve 65. The cam-groove 70 directs movement of the lever 71 to a comparatively 40 slight extent, merely sufficient to depress the plunger 20 until it contacts with the roller 41 without relatively depressing—at least to any material extent—the plunger 18. The cam-groove 72, however, is of such configuration 45 as to impart to the lever 73 a longer stroke, in this case causing depression of the plungers with the effect, first, of seating the solid interior plunger against the head or cover 57, which has been placed in or delivered 50 to the seat 58, and then continuing downward movement of the plunger 18 against the action of the spring 22, completely telescoping the plunger 20 and scraping therefrom the ring 74 of the lining compound 55 which is then pressed into the groove or gutter 59 of the head or cover, substantially along the middle line of the bottom thereof, as clearly shown in Fig. 4. The covers 57 are each placed in or delivered to 60 the seat 58 in a heated condition, wherefore, the plungers and the composition being comparatively cool—and it will be noted that the plungers have ample time for cooling between operations at the cover-lining station—the packing ring will adhere to the

cover when the plunger 18 is raised under action of the spring 33 after depression of the arm 68.

To rotate the plunger 20 at the “receiving” station, when it is in contact with the 70 rotating feed-roller 41, I have shown as a preferred construction a grooved pulley 75 on the power shaft 40 and a similar pulley 76 on a short vertical shaft 77 journaled in bearings in the standard or bracket 78 75 mounted on the frame 7, around which passes the rope-belt 79, idlers 80 and 81 being interposed to provide for the necessary change of direction. On the short shaft 77 is mounted the roller 82 so positioned that 80 when each plunger mechanism is brought over the feed-roller 41, the roller 24 mounted on the shank of the plunger 20 and said roller 82 will be brought into contact with each other and the former be frictionally rotated by the latter to rotate the plunger 20 as it is depressed against the roller 41.

The plunger 20, with its ring 74 of lining compound thereon, having been raised from the feed-roller 41, is first carried by the revolving arm to an idler station and then to the lining station where the ring is positively delivered to proper position in the cover groove or gutter in the manner described, during which time the compound 95 will have become of denser consistency through evaporation.

Many modifications of minor details of my improved can-cover lining machine will doubtless readily suggest themselves to those skilled in the art to which it appertains, and I therefore do not desire to limit my invention to the specific construction herein shown and described.

I claim:

1. In a can-cover lining machine, the combination, with means for forming and holding a gasket of semi-liquid material, of means for subsequently depositing said gasket around the edge of a can-cover. 110
2. In a can-cover lining machine, the combination, with means for forming and holding a gasket of semi-liquid material, of means subsequently operable to positively deliver said gasket to and position the same 115 around the edge of a can-cover.
3. In a can-cover lining machine, the combination, with means for forming and holding a gasket of semi-liquid material, of means for subsequently depositing the 120 formed gasket in the peripheral groove of a can-cover.
4. In a can-cover lining machine, the combination, with means for forming and holding a gasket of semi-liquid material, of 125 means subsequently operable to positively deliver the formed gasket to and position the same in the peripheral groove of a can-cover.
5. In a can-cover lining machine, the com- 130

1. In a carrying form, means for delivering thereto and forming thereon an adhering ring of semi-liquid lining compound, means for conveying said form to a lining station, and means for depositing said ring around the edge of a can-cover at said station.
2. In a can-cover lining machine, the combination of a carrying form, means for delivering thereto and forming thereon an adhering ring of semi-liquid lining compound, means for conveying said form to a lining station, and means for depositing said ring around the edge of a can-cover at said station.
3. In a can-cover lining machine, the combination of a carrying form, means for delivering thereto and forming thereon an adhering ring of semi-liquid lining compound, means for conveying said form to a lining station, and means for positively delivering said ring to and positioning the same around the edge of a can-cover at said station.
4. In a can-cover lining machine, the combination of a carrying form, means for delivering thereto and forming thereon an adhering ring of semi-liquid lining compound, means for conveying said form to a lining station, and means for depositing said ring around the edge of a can-cover at said station.
5. In a can-cover lining machine, the combination of a carrying form, means for delivering thereto and forming thereon an adhering ring of semi-liquid lining compound, means for conveying said form to a lining station, and means for positively delivering said ring to and positioning the same around the edge of a can-cover at said station.
6. In a can-cover lining machine, the combination of a carrying form, means for delivering thereto and forming thereon an adhering ring of semi-liquid lining compound, means for conveying said form to a lining station, and means for positively delivering said ring to and positioning the same around the edge of a can-cover at said station.
7. In a can-cover lining machine, the combination, with a rotating roller and means for delivering to the cylindrical face thereof an adhering coating of semi-liquid material, of a carrying form, means for rotating said form with the edge thereof in contact with said roller to scrape therefrom a formed gasket of said material, means for conveying said form to a lining station, and means for depositing said gasket around the edge of a can-cover at said station.
8. In a can-cover lining machine, the combination, with a rotating roller and means for delivering to the cylindrical face thereof an adhering coating of semi-liquid material, of a round carrier, means for rotating said carrier and simultaneously bringing the edge thereof into contact with said roller to scrape therefrom a ring of said material, means for conveying said carrier to a lining station, and means for depositing said ring around the edge of a can-cover at said station.
9. In a can-cover lining machine, the combination of a plurality of intermittently traveling carrying forms, means for delivering to and forming on each thereof in turn while in a condition of rest an adhering ring of semi-liquid lining compound, and means for depositing the ring on each form successively around the edge of a can-cover.
10. In a can-cover lining machine, the combination of a series of carrying forms mounted to revolve in a common orbit, means for intermittently revolving said forms, means for delivering to and forming on each thereof in turn while in a condition of rest an adhering ring of semi-liquid lining compound, and means operating coincidentally with said last-mentioned means for depositing the ring on a preceding form around the edge of a can-cover.
11. In a can-cover lining machine, the combination, with a rotating roller and means for delivering to the cylindrical face thereof an adhering coating of semi-liquid material, of a plurality of intermittently traveling carrying forms, means for rotating one of said forms when in a condition of rest with the edge thereof in contact with said

roller to scrape therefrom a formed gasket of said material, means for conveying said forms successively to a lining station, and means for depositing the gasket on each form successively around the edge of a can-cover at said station.

12. In a can-cover lining machine, the combination, with a rotating roller and means for delivering to the cylindrical face thereof an adhering coating of semi-liquid material, of a plurality of intermittently traveling round carriers, means for rotating one of said carriers when in a condition of rest and simultaneously bringing the edge thereof into contact with said roller to scrape therefrom a ring of said material, means for conveying said carriers successively to a lining station, and means for depositing the ring on each carrier successively around the edge of a can-cover at said station.

13. In a can-cover lining machine, the combination, with a rotating roller and means for delivering to the cylindrical face thereof an adhering coating of semi-liquid material, of a series of carrying forms mounted to revolve in a common orbit, means for intermittently revolving said forms, means for rotating one of said forms when in a condition of rest with the edge thereof in contact with said roller to scrape from the latter a formed gasket of said material, and means operating coincidentally with said last-mentioned means for depositing the gasket on a preceding form around the edge of a can-cover.

14. In a can-cover lining machine, the combination, with a rotating roller and means for delivering to the cylindrical face thereof an adhering coating of semi-liquid material, of a series of carriers mounted to revolve in a common orbit, means for intermittently revolving said carriers, means for rotating one of said carriers when in a condition of rest and simultaneously bringing the edge thereof into contact with said roller to scrape therefrom a ring of said material, and means operating coincidentally with said last-mentioned means for depositing the ring on a preceding carrier around the edge of a can-cover.

15. In a can-cover lining machine, the combination of a carrying form, means for delivering to and forming around the lower edge thereof an adhering ring of semi-liquid lining compound, means for conveying said form to a lining station, and means for depositing said ring around the edge of a can-cover at said station, said last-mentioned means comprising a hollow plunger in telescopic arrangement with said form.

16. In a can-cover lining machine, the combination of a plurality of intermittently traveling carrying forms, means for delivering to and forming around the lower edge

- of each thereof in turn while in a condition of rest an adhering ring of semi-liquid lining compound, and means for depositing the ring on each form successively around the 5 edge of a can-cover, said last-mentioned means comprising a hollow plunger in telescopic arrangement with each of said forms.
17. In a can-cover lining machine, the combination of a plurality of intermittently 10 traveling carrying forms, means for delivering to and forming around the lower edge of each thereof in turn while in a condition of rest an adhering ring of semi-liquid lining compound, means for conveying said forms successively to a lining station, and 15 means operating coincidently with said delivering and forming means for depositing the ring on a preceding form around the edge of a can-cover at said station, said 20 means comprising a hollow plunger in telescopic arrangement with said form.
18. In a can-cover lining machine, the combination of a series of carrying forms mounted to revolve in a common orbit, 25 means for intermittently revolving said forms, means for delivering to and forming around the lower edge of each thereof in turn while in a condition of rest an adhering ring of semi-liquid lining compound, 30 and means operating coincidently with said delivering and forming means for depositing the ring on a preceding form around the edge of a can-cover, said last-mentioned 35 means comprising a hollow plunger in telescopic arrangement with each of said forms.
19. In a can-cover lining machine, the combination, with a rotating roller and means for delivering to the cylindrical face thereof an adhering coating of semi-liquid 40 material, of a carrying form, means for rotating said form with the edge thereof in contact with said roller to scrape therefrom a formed gasket of said material, means for conveying said form to a lining station, and 45 means for depositing said gasket around the edge of a can-cover at said station, said last-mentioned means comprising a hollow plunger in telescopic arrangement with said form.
20. In a can-cover lining machine, the combination, with a rotating roller and means for delivering to the cylindrical face thereof an adhering coating of semi-liquid material, of a round carrier, means for rotating said carrier and simultaneously 55 bringing the edge thereof into contact with said roller to scrape therefrom a ring of said material, means for conveying said carrier to a lining station, and means for depositing 60 said ring around the edge of a can-cover at said station, said last-mentioned means comprising a hollow plunger in telescopic arrangement with said carrier.
21. In a can-cover lining machine, the combination, with a rotating roller and 65
- means for delivering to the cylindrical face thereof an adhering coating of semi-liquid material, of a plurality of intermittently traveling round carriers, means for rotating one of said carriers when in a condition of rest and simultaneously bringing the edge thereof into contact with said roller to scrape therefrom a ring of said material, means for conveying said carriers successively to a lining station, and means for depositing the ring on each carrier successively around the edge of a can-cover at said station, said last-mentioned means comprising a hollow plunger in telescopic arrangement with each of said carriers. 70
22. In a can-cover lining machine, the combination, with a rotating roller and means for delivering to the cylindrical face thereof an adhering coating of semi-liquid material, of a series of carriers mounted to 75 revolve in a common orbit, means for intermittently revolving said carriers, means for rotating one of said carriers when in a condition of rest and simultaneously bringing the edge thereof into contact with said roller to scrape therefrom an adhering ring of 80 said material, and means operating coincidently with said ring-forming means for depositing the ring on a preceding carrier around the edge of a can-cover, said last-mentioned means comprising a hollow plunger in telescopic arrangement with each of said carriers. 85
23. In a can-cover lining machine, the combination of a carrying form, means for delivering to and forming around the lower edge thereof an adhering ring of semi-liquid lining compound, means for conveying said form to a lining station, and means for depositing said ring around the edge of a can-cover at said station, said last-mentioned means comprising a hollow plunger in telescopic arrangement with said form and operating means which first seats said form on the cover and then actuates said plunger. 90
24. In a can-cover lining machine, the combination, with an intermittently rotating turret and a series of vertically reciprocable forms carried thereby, of means for delivering to and forming on each of said forms successively a gasket of semi-liquid material, a reciprocable hollow plunger in telescopic arrangement with each of said forms, and means operable after continued rotation of said turret to first depress each form successively and then depress the plunger thereon to scrape the gasket from the form and deposit the same around the edge of an underlying can-cover. 105
25. In a can-cover lining machine, the combination, with an intermittently rotating turret, a series of vertically reciprocable forms carried thereby, and a reciprocable hollow plunger in telescopic arrangement with each of said forms, of means for 110
- 115
- 120
- 125
- 130

- delivering to and forming on each of said forms successively while said turret is in a condition of rest a gasket of semi-liquid material, and means operable coincidently with the gasket-forming operation to first 5 depress an advanced form and then depress the plunger thereon to scrape the gasket from the form and deposit the same around the edge of an underlying can-cover.
- 10 26. In a can-cover lining machine, the combination, with an intermittently rotating turret, a series of vertically reciprocating and yieldingly supported forms carried thereby, and an independently reciprocable 15 hollow plunger in telescopic arrangement with each of said forms, of a rotating roller, means for delivering to the cylindrical face thereof an adhering coating of semi-liquid
- material, means for rotating one of said forms when in a condition of rest with the 20 edge thereof in contact with said roller to scrape therefrom an adhering ring of said material, and means operating coincidently with said ring-forming means to first depress an advanced form and then depress the 25 plunger thereon to scrape the ring from said form and deposit the same around the edge of an underlying can-cover.

In testimony of the foregoing, I have hereunto set my hand in the presence of 30 two witnesses.

JULIUS BRENZINGER.
